UNITED STATES PATENT OFFICE.

SPENCER OTIS, OF CHICAGO, ILLINOIS, ASSIGNOR TO NATIONAL PATENT HOLDING COMPANY, OF SOUTH DAKOTA, OF RAPID CITY, SOUTH DAKOTA, AND CHICAGO, ILLINOIS, A CORPORATION OF SOUTH DAKOTA.

TRUCK-BOLSTER FOR RAILWAY-CARS.

SPECIFICATION forming part of Letters Patent No. 739,911, dated September 29, 1903.

Application filed August 29, 1902. Serial No. 121,435. (No model.)

To all whom it may concern:

Be it known that I, SPENCER OTIS, a citizen of the United States, residing at Chicago, in the county of Cook and State of Illinois, have 5 invented certain new and useful Improvements in Truck-Bolsters for Railway-Cars, of which the following is a specification.

This invention relates to that class of bolsters which are used in the construction of 10 trucks for railway-cars, and particularly to the specific construction thereof, all of which will more fully hereinafter appear.

The principal object of the invention is to provide a simple, economical, and efficient 15 bolster for a car-truck.

A further object of the invention is to provide a bolster for a car-truck with a journal at each end by which it may be rotatably mounted in position.

20 Further objects of the invention will appear from an examination of the drawings and the following description and claims.

The invention consists principally in a truck-bolster provided with a body portion 25 having a cylindrical journal portion at each end.

The invention consists, further and finally, in the features, combinations, and details 30 of construction hereinafter described and claimed.

In the accompanying drawings, Figure 1 is a side elevation of a truck-bolster constructed in accordance with these improvements; Fig. 2, a plan view of the same, shown partly in 35 section and looking at it from above; Fig. 3, an enlarged cross-sectional view, taken on line 3 of Fig. 1, looking in the direction of the arrow; Fig. 4, a longitudinal sectional detail, taken on line 4 of Fig. 2, looking in the direction of the arrow; and Fig. 5, a cross-sectional view of a modified form of the construction shown in Fig. 3, in which the cylindrical journal-bearing portion is made continuous instead of in broken or semicylindrical portions, as shown in Fig. 3.

In the art to which this invention relates it is well-known that it is highly desirable to

have a car-truck that will be of such construction that one or both side frames may rock or 50 swivel independently of each other and of the truck-bolster. To accomplish this result, a truck-bolster with cylindrical journals at each end is very desirable, and to provide such a bolster is the prime object of this invention. In illustrating and describing these 55 improvements it is only deemed desirable or necessary to describe bolster herein, as it can be adapted to various forms of trucks, which do not form any part of the invention.

In constructing a truck-bolster in accordance with these improvements I provide a main body portion *a* of the desired size, shape, and strength to support the superstructure in the desired manner. This body portion is preferably made in the shape of a metallic I- 65 beam, having web portions *b*, an upper flange *c*, and a lower flange *d*, interposed strengthening-ribs *e*, and a central tubular portion *f*, through which the king-bolt passes.

In this particular improvement the truck- 70 bolster is provided with cylindrical journals *g* at each end, having flanges *h* on the outside and shoulders *i* on the inner side of the bolster only, as shown particularly in Figs. 1 and 2. The journals of the bolster have their 75 bearings in the side frames of a car-truck in such a manner as to allow such side frames to rock independently of each other while supporting the car and to assist in tying the truck-frame together.

The center bearing *k*, upon which the usual body-bolster rests, is arranged in the upper flange of the bolster substantially at or near the axial center of the end journals, all of which tends to keep the bolster in normal position and prevent rocking, which might otherwise occur if the seat were at any distance above the center. Integral side bearings are also provided in the desired position.

I claim—

1. As a new article of manufacture, a car-bolster formed of metal having integral cylindrical journals at each end and a center bearing on the upper portion arranged substan-

tially at or near the axis of the cylindrical end journals, substantially as described.

2. As a new article of manufacture, a metallic truck-car bolster, a body portion formed substantially I-shaped in cross-section and provided with integral cylindrical journals at each end, and a center bearing on the upper

flange thereof arranged at or near the axial center of the cylindrical journals, substantially as described.

SPENCER OTIS.
